UNITED STATES PATENT OFFICE.

WILLIAM A. LYONS, OF LITCHFIELD, MINNESOTA.

TIME-INDICATING DEVICE.

1,397,319.

Specification of Letters Patent. Patented Nov. 15, 1921.

Application filed December 4, 1920. Serial No. 423,267.

To all whom it may concern:

Be it known that I, WILLIAM A. LYONS, a citizen of the United States, residing at Litchfield, in the county of Meeker and State 5 of Minnesota, have invented certain new and useful Improvements in Time-Indicating Devices, of which the following is a specification.

This invention relates to time and direction indicating devices for use in railroad stations, hotels and public places generally and more particularly to that class, having indicia carrying mechanism arranged in connection with clock work having ordinary 15 time indicating clock hands.

An object of the invention is to provide, in a device of the class described an improved novel construction, whereby a rotary partly visible placard, arranged concentric 20 with a clock dial, and with the spindle whereon are supported the clock hands, may be conveniently rotated to any arbitrarily selected position and held so positioned, independently of the clock spindle, the novel 25 construction, rendering the device commercially practical, in that the placard may be readily removed from the rear of the device and yet be visible from in front of same.

A further object of the invention, is to 30 provide a device of the class described which will be dust proof, light in weight, compact and cheap of construction, as well as efficient and neat in appearance.

In the drawings:—
35 Figure 1 is a front view of my improved device, partly broken away.

Fig. 2 is a rear view of one of the time and direction indicating units partly broken away.

40 Fig. 3 is a sectional view on line 3—3 of Fig. 2.

Fig. 4 is a sectional view on line 4—4 of Fig. 1, drawn on an enlarged scale.

Fig. 5 is a front view of the placard or 45 rotary indicia carrying element, and.

Fig. 6 is a fragmentary front view of one of the clock dials.

A designates a rectangular, comparatively thin casing, comprising top and bottom 50 walls 1, and side walls 2, the walls having longitudinally a shoulder 3, whereon rests the inner supporting or partition wall 4, suitably secured to said shoulder. The front wall 5 of the casing, has apertures 6, shown 55 arranged in two vertically spaced horizontal rows, each aperture representing the center

of a clock dial 7 forming part of what will hereinafter be referred to as a whole, as a time indicating unit. A single unit will be described as all units are similar. Opposite each aperture, cutting through the supporting wall 4, is the bore 8, surrounded by the rearwardly extending sleeve 9. Having a hub 11 bored to fit around said sleeve is the circular placard or display disk 10, said hub being flush with the sleeve, and extending through and slightly beyond the opposite side of said disk, so that the latter will be slightly spaced from the wall 4 to render it freely rotatable. Perforations 12 arranged in a circle concentric with the dial 7, form radially disposed teeth 13, adapted to mesh with the stud gear 14 rigid on the shaft 15. The shaft 15 is horizontally disposed in a plane parallel with the wall 4 and 70 is journaled on the bracket 16, which latter is firmly secured to the walls 4 and 5 and serves as a spreader therebetween. The edge of the gear 14 extends through a slotted opening 17 in the wall 4, so as to mesh with the teeth 13. Rigid on the shaft 15, is the miter gear 18, in mesh with the miter gear 19, the latter rigid on the vertically disposed stem 20, said stem being journaled at its lower end in the bracket 21, and at its 75 upper, in the top wall 1 of the casing. The stem extends through and beyond the casing, and is provided with a thumb nut 22. By grasping the nut with the hand and turning same, the disk may be revolved to any 80 arbitrarily selected position. The wall 5 which is preferably of sheet metal forms the back of the casing A, and is suitably screwed to the walls 2, so that it may be easily removed. The wall is provided with doors 95 15" adjacent the disks of the several time indicating units (of which any number may be employed) so that they may be easily removed for the purpose of changing, when desired, the declaratory matter displayed 100 thereon.

Suitably secured on the front of the wall 5, concentric with the apertures 6, is the ring 23 suitably beaded at its free edge to hold the glass 24, the latter resting upon the ring insert 25, to hold it positioned. Cutting through the wall 5 above and adjacent the ring 23 and concentric therewith, is the arched opening 26, said opening extending a distance on either side of a vertical line intersecting the center of the disk. Opposite the opening 26, is a similarly

shaped opening 27, cutting through the wall 4, so as to expose a section of the disk 10 to view, through said openings. The opening 26 is somewhat larger than the opening 27, so as to render the disk visible, when the device is hung in elevated position. A tapered lining 28 extending between the walls 4 and 5 keeps the dust from entering the casing. The disk 10, shown, 10 is impressed with the words, North—South—East and West designating the points of the compass to indicate the direction in which a certain train is traveling and with A. M. and P. M. to indicate 15 whether before or past meridian. To indicate the hour and minute of day, an ordinary clock dial is used, having an hour hand 29 and minute hand 30. For conveniently moving the hands in synchrony, by simply 20 turning a button positioned in lateral alinement with the button 22, the following described mechanism is provided, the parts thereof being novelly arranged to effect compactness, whereby the space between the 25 walls 4 and 5 is kept small and the device rendered neat in appearance. Journaled in the bore 8, is the hand arbor 31, extending forwardly through the aperture 6, and carrying at its outer extremity the minute hand 30. The rearmost portion of the arbor is reduced in diameter to form a stud 30 suitably threaded to receive the lock nuts 32, which latter overlap the hub 11 of the disk, thereby serving to hold it positioned. Shown integral with the arbor, is the gear 33 meshing with the gear 34, which latter is rigidly mounted on the shaft 35. Rigid 40 on the quill 36, which latter rotatably fits over the arbor and extends to the minute hand beyond the wall 5, is the gear 37, meshing with the pinion 38 on the shaft 35. The quill carries at its forward end, the hour hand 29. Rigid on the shaft 35, is the crown wheel 39 in mesh with the pinion 40, the latter rigid on the shaft 41 journaled 45 in the bracket 42. The shaft 42 is disposed parallel to the shaft 15, and the bracket 42 extends between the walls 4 and 5 after the manner of bracket 16.

Opposite the pinion 40, on the shaft 41, is the miter gear 44, the latter rigidly mounted on the vertically disposed stem 45 extending through the top wall of the casing, and having a thumb nut 45' at its free 50 end, similar to the nut 22. The stem 45 has bearing in a bracket similar to bracket 21 said brackets being suitably secured to the supporting wall 4. The train of gears 37, 38, 39 and 40 are so proportioned in diametral pitch, as compared with the train formed by the gears, 33, 34, 39 and 40, as to cause 55 the hour and minute hands to rotate at ratio of 1 to 12. By turning the thumb nut 45' the hands may be conveniently moved to indicate the time of day. By

using a crown wheel in the manner shown, a small pinion (40) can be used, which enables me to keep the space between the walls 4 and 5 very small. As this space increases, the disk 10 (Fig. 4) becomes shaded and thereby rendered more or less difficult to read the arched opening 26 becoming too deep in proportion to its width. In a device of this kind the disks must be easily removable, to render it commercially practicable, because of frequent changes in the printed matter thereon, it being understood that the device may be used in schools for announcing lecture topics and the time of delivery of the lecture, and for many other analogous purposes. By opening the door 15" and removing the units 32 the disk of any unit may be easily removed. Suitable label holders B, above the apertures 27 are provided, to hold cards carrying the names of the particular railroad to which the several time indicating devices relate.

I claim:

1. A device of the class described, comprising a pair of spaced plates held in parallelism, one behind the other, a plurality of units of the class described, spaced from one another, supported on said plates, each of said units comprising an arbor perpendicular to said plates and extending between and through and beyond said plates and journaled in the rear plate thereof, a clock dial concentric with said arbor on the front plate, an aperture above said clock dial cut through each of said plates one behind the other, hand operable time indicating mechanism, including an hour and a minute hand supported on said arbor in front of said dial, said indicating mechanism extending laterally and upwardly between said plates around one side of said apertures to avoid obstruction of the line of vision through same and to and beyond the outer edge of said plates to be operated thereat, and hand operable sign display mechanism, including a rotary placard rotatably supported to the rear of the rear plate of said plates in concentric relation with said arbor, and extending over the aperture in said rear plate, said sign display mechanism extending laterally and upwardly around the other side of the aperture in said rear plate opposite said time indicating mechanism to avoid obstruction of the lines of vision through same, and to and beyond the outer edge of said plates to be operated thereat.

2. A device of the class described, comprising a pair of spaced plates held in parallelism, one behind the other by means of surrounding walls, a plurality of units of the class described, spaced from one another, supported on said plates, each of said units comprising a clock dial on the front plate of said plates, hand operable mechanism between said plates includ-

ing clock hands extending over said dial, operable from a position outside of said surrounding walls, for moving said hands in synchrony to indicate any selected time 5 of day, an opening cut through both of said plates over said clock dial, a device, adapted to carry indicia, movably mounted to the rear of the rear plate of said plates in a manner to pass said aperture, when actu-

ated so as to be visible from in front of 10 the front plate of said plates, and hand operable means operatively connected with said indicia carrying device and extending to a position outside of said surrounding walls to operate said device therefrom. 15

In testimony whereof I affix my signature.

WILLIAM A LYONS.
